COMBINED CABINET AND BENCH UNIT

Albert C. Weber, 600 Glen Ridge Drive, Glenview, Ill.

Filed Dec. 14, 1960, Ser. No. 63,220

Term of patent 3½ years

(Cl. D33—12)

FIG. 1 is a front perspective view of the combined cabinet and bench unit showing my design in assembled position;

FIG. 2 is a perspective view showing the bench removed from the nesting holes in the face of the cabinet and placed in operating position.

The side not shown is the same as that shown in FIGURE 3 while the back of the cabinet is plain and unornamented.

I claim:

The ornamental design for a combined cabinet and bench unit, substantially as shown and described.
